*Horatio Smith
Henry Brown.*

Des. 1819

Garrettson Smith and Henry Brown of Philadelphia, Penn.
Assors to

H. C. March and E. Sisler, of Lawrenceville, Chester Co Penn.

Letters Patent No 1819-Dated Sept. 22, 1863.

Design for a Stove.

The schedule referred to in these Letters Patent and making part of the same.

To all whom it may concern:

Be it known that we, Garrettson Smith and Henry Brown, of the City and County of Philadelphia, State of Pennsylvania, have invented or produced a new and original design for a Stove; and

Dec. 1819

we do hereby declare the accompanying drawing, with the following explanation of the same, to form a full, clear and exact description of the said Design.

The figure in the annexed drawing represents our design for stove, in perspective.

The bottom plate A, of the stove has on the edge the ornaments illustrated in the drawing, and is supported on the ornamental legs B.

On the bottom plate rests the base D, which is ornamented in a manner clearly illustrated in the drawing, and on this plate rests the egg shaped and fluted fire pot E, which is surrounded, at a point, where it is largest in diameter, with the ornamental ring F.

Another ornamental ring G, rests on the upper edge of the fire-pot, and on this ring rests the cylinder H, which is composed of a number of plates ornamented in the manner clearly indicated in the drawing, the front plate of the cylinder being furnished with an ornamental door as shown.

I, is the cap of the cylinder, the shape and ornamentation of this cap being too clearly indicated in the drawing to need description.

We claim the ornamental figures and forms represented in and by the accompanying drawing, the whole forming an ornamental design for a stove.

In testimony whereof, we have signed our names to this specification in the presence of two subscribing witnesses.
